CLAIM

The ornamental design for the broken olla chair, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright and trade dress rights whatsoever.

FIG. 1 is a front elevational view of a broken olla chair showing my new design, the stipple shading shown on the seat to show the texture of the seat.

FIG. 2 is a right side elevation view thereof.

FIG. 3 is a top view thereof.

FIG. 4 is a left side elevation view thereof.

FIG. 5 is a rear elevation view thereof; and,

FIG. 6 is a bottom elevation view thereof.
